JEWELRY BOX

Samuel Tylon, Cleveland, Ohio

Application May 26, 1950, Serial No. 164,499

1 Claim. (Cl. 206—76)

1

This invention relates to jewelry boxes.

An object of this invention is to provide a jewelry box which is constructed in the form of a horseshoe and is provided with a receptacle for holding a wedding ring or the like.

Another object of this invention is to provide a jewelry box in the shape of a horseshoe having a receptacle extending from the bight of the shoe with a cover hinged to the bight of the shoe. The cover includes a rearwardly projecting shank seating in a slot in the upper side of the bight of the shoe and the bight of the shoe is formed with a stop for holding the receptacle cover in open position.

With the above and other objects in view, my invention consists in the arrangement, combination and details of construction disclosed in the drawings and specification, and then more particularly pointed out in the appended claims.

In the drawings:

Figure 1 is a plan view of a jewelry box constructed according to an embodiment of this invention.

Figure 2 is a sectional view taken on the line 2—2 of Figure 1.

Figure 3 is a detailed side elevation of the box with the cover in open position.

Figure 4 is a sectional view taken on the line 4—4 of Figure 3.

Figure 5 is a sectional view taken on line 5—5 of either Figure 2 or 4.

Referring to the drawings, the numeral 10 designates generally a base in the form of a horse shoe which includes a bight portion 11 and side members 12. The bight portion 11 is provided with a downwardly extending lug or supporting member 13, and each side member 12 is provided with a caulk 14 forming a foot or supporting member. A receptacle generally designated as 15 is formed on the inside of the horse shoe 10 extending forwardly from the bight thereof and includes a bottom wall 16 formed integral with the sides 12 and the forward portion of the bight 11. A front wall 17 extends upwardly from the bottom wall 16 and is formed with a centrally disposed cutout or finger recess 18. A pad or cushion member 19 is adapted to be disposed within the receptacle 15 and includes a band or strap 20 extending over the upper side of the cushion 19 so as to removably hold a wedding ring 21 on the cushion 19.

A cover or closure generally designated as 22 engages over the receptacle 15 and includes a plate 23 having a relatively narrow shank 24 extending from the rear thereof, and the shank 24 is adapted when the cover 15 is in closed position to seat in a slot or recess 25 formed in the upper side of the bight 10. The shank 24 is provided with a hinge barrel 26 at the rear thereof through which a pintle 27 engages, and the pintle 27 engages in hinge barrels 28 formed on the rear of

the bight 11. The bight 11 is provided at the rear thereof with an upwardly projecting lug or stop member 29 which is engageable by the shank 24 when the cover 15 is raised upwardly to open position so as to hold the cover 15 in upwardly and rearwardly inclined open position.

The cover 15 also includes a forward flange 30 extending downwardly from the plate 23 which is adapted to overlap the front wall or flange 17 of the receptacle 15. The plate 23 is formed on the upper side thereof with a bezel 31 within which a crystal or transparent plate 32 is adapted to engage, and an indicia bearing sheet 33 is positioned between the crystal 32, and the upper side of the plate 23.

The jewelry box hereinbefore described may be formed out of either metal, plastic, or other suitable material, and will provide an attractive receptacle for holding a wedding ring or other article of jewelry.

What is claimed is:

A jewelry box comprising a U-shaped base simulating a horseshoe, caulks carried by the bight and the opposite sides of said base, and a receptacle having walls terminating below the top of said base carried by said base, said receptacle comprising a bottom wall fixed between said sides and fixed to the inner side of said bight, an upstanding front wall fixed to said bottom wall having a cutout center portion, a cover engaging over said receptacle formed of a top plate of a configuration adapted to seat within the bight of said base on the top of said walls of said receptacle flush with the top of said base, a depending flange at the forward edge of said top plate and engageable over said front wall, a flat shank extending rearward of said top plate, said bight having a recess in the upper side thereof within which said shank engages, said base having a transverse channel at the end of said recess, a hinge barrel carried by the rear of said shank, a pair of hinge barrels carried by the rear of said bight, one of said pair of hinge barrels seating in said channel, a pintle engaging through said hinge barrels, a bezel on said top plate, an indicia bearing sheet in said bezel, and a transparent cover for said sheet secured by said bezel, said bezel conforming in configuration to the interior of the bight of said base, surrounding the periphery of said top plate and extending across the base of said shank.

SAMUEL TYLON.
